REFRIGERATOR DOOR

Clifford A. Rehling, St. Paul, Minn., assignor to
 Seeger Refrigerator Company, St. Paul, Minn.,
 a corporation of Minnesota

Application November 21, 1928, Serial No. 320,931

9 Claims. (Cl. 20—35)

My invention relates to refrigerator doors wherein it is designed to provide a door having a simple construction which may be easily assembled and when put together forms a door structure with an outer finished enameled surface and an inner enameled surface over the major portion of the inside of the door. A primary feature of my invention is to provide means of holding the non-metallic frame structure to the outer enameled metal in an effective manner facilitating easy assembly. This structure provides means of making the non-metallic frame in a complete unit and then attaching the same to the outer facing made and provided for the door.

It is also a feature of my invention to provide a particular door structure wherein the outer face of the same is made with an enameled metal covering, an insulating filler or body unit, and an enameled inner covering, the insulating material spacing the inner and outer enameled metal coverings apart so as to prevent the carrying of heat or cold from the outside in or from the inside out when my door is used on the refrigerator.

All of the objects, together with other details and features will be more fully and clearly set forth hereinafter.

In the drawing forming part of this specification:

Figure 1 is an inside view of my refrigerator door, a portion of which is broken away.

Figure 2 is a perspective view of the insulating frame unit of my door.

Figure 3 is an enlarged cross section of the door transversely of the same and a part of which is broken away.

Figure 4 is a detail cross section of a portion of my door.

In the drawing my door A is designed to be used particularly as a refrigerator door wherein the same is built up with a unit insulating frame B made of wood or other suitable material illustrated in the unit in Figure 2.

The frame B of the door A is adapted to provide a means of insulation between the outer enameled metal facing 11 and the inner enameled metal facing 12. The frame B may be made of any suitable insulating material and has its sides 13 and ends 14 connected together by mitered joints or in any other suitable manner. Naturally the frame may be formed of a single piece of a fibrous insulating material. However, it is very practical to use a frame made of wood with the sides 13 and the ends 14 connected together in a unit as illustrated in Figure 2.

After the frame B has been completed and the

same is formed with a groove or recess 15 to receive the inner edge 16 of the inner facing 12 or with the shoulder portion 17 projecting up from the same to which the inner inturned edge 16 of the inner facing 12 is attached as illustrated in Figure 4, the frame is then ready to be assembled with the outer facing 11 and the inner facing 12. It is important that this assembly of the unit frame B be made easily and in such a manner as to securely hold the unit frame B in position to form a strong sturdy door construction.

I accomplish these results in a simple manner which forms one of the important features of this invention. When the frame B is completed as a unit, as illustrated in Figure 2, one or more finger members 18 are attached by the screws 19 to one of the sides of the unit B. The finger members 18 are formed with an inclined outer free end 20 which is adapted to engage beneath the inturned marginal edge 21 of the outer facing 11 of the door. These fingers 18 have a sufficient spring nature in the inclined end 20 to provide spring finger members to cause one side, such as 13 of the frame B, to be drawn up tightly against the insulating sheet 22 and against the inner face of the outer sheathing 11 of the door A. The insulating sheet 22 may or may not be used in the making of my door and where it is used the door frame B is drawn in a manner to press tightly against the insulating sheet by the engagement of the spring fingers 20 under the inturned edge 21 of the door facing 11. By this means of construction the unit frame B may be hooked under the inturned edge 21 of the facing 11 on one side and the other side 13 of the door frame B is drawn tightly against the inner surface of the outer sheathing 11 by means of the screws 24 which attach the hardware, such as 25, to the door A.

Thus by means of the spring fingers 18 and the screws 24 I provide a very simple and effective means of holding the insulating frame B in proper position within the outer facing 11. This is an important feature of the invention as it eliminates extra operations and also accomplishes the desired results in a much better manner than heretofore. The spring fingers 18 hold the frame B under tension to the facing 11 and thus the frame B is always tightly supported within the enameled metal facing 11 and will not rattle or become loose which is very important in refrigerator doors. It also permits the frame B to be made very sturdy so as to form the body and insulating separator between the members 11 and 12.

The inner face 12 may be secured as illustrated in Figure 4 by attaching the inturned edge 16 of the inner metal enameled facing 12 to the shoulder 17 of the insulating frame B by the 5 screws 26. Then the molding 27 may be attached over the edge 16 and the screws 26 to form an outer edge over the inwardly extending edge 16 of the inner plate 12. This construction is fully illustrated in Figure 4 and by using the 10 spring fingers 18 the frame B is held firmly and tight within the outer facing 11. The attachment of the inner face plate 12 assists in providing a rigid door construction to brace the frame B and any suitable insulating material 15 may be used within the frame B and inside of the inner face plate 12 to provide the proper insulation to the body of the door A when it is complete.

In accordance with the patent statutes I have 20 described the principles of operation of my door structure and while I have endeavored to set forth the best embodiment thereof it should be borne in mind that obvious changes can be made within the scope of the following claims 25 without departing from the purpose and intent of the invention.

I claim:

1. A refrigerator door including, an outer metal facing having an inturned marginal edge, an 30 insulating frame adapted to fit in said door, and spring fingers carried by said frame adapted to engage beneath said marginal edge to hold said frame under spring tension within said outer metal facing.
2. A refrigerator door including, an insulating frame member, spring fingers carried by said frame member, an outer metal facing for said door, an inturned edge formed on said facing adapted to be engaged by said spring fingers to 40 hold one side of said door tightly against the inner surface of said outer facing, and means for attaching the other side of said door by the screws holding the hardware to the outer metal facing of said door.
3. A refrigerator door including, an outer and inner metal facing, an insulating unit frame, and means for securing said frame to said outer facing by spring engaging members on one side, and the members supporting the hardware on 50 the other side of said inner facing being attached to said frame.
4. A refrigerator door comprising, an insulating unit frame, inner and outer metal face plates for said frame, fingers secured to said frame and engaging said outer facing to secure said frame to said outer facing along one side, and means for holding the other side tightly in engagement with said outer facing along another 60 side to rigidly support said frame on said outer

facing, and means for supporting said inner facing on said frame.

5. A refrigerator door including, an outer facing, an insulating unit frame, and means for attaching said frame to said outer facing including fingers carried by said frame and engaging said outer facing, and means for holding a side of said frame remote from said fingers fixedly against said outer facing.

6. A refrigerator door comprising, a unit rectangular insulating frame, fingers carried by one side of said frame, an outer metal sheathing for said frame having an inturned marginal edge, said frame being attached to said outer sheathing by said fingers engaging under said marginal edge on one side, and the other side of said frame being held tightly against the inner surface of said outer sheathing by the attachment of the hardware thereto, and an inner metal sheathing adapted to cover the major portion of the inner 20 surface of said door and supported by said frame.

7. A door including an insulating frame, an outer metal sheathing for said door, hook-like spring means on one side of said frame adapted to securely engage one side of said sheathing, and 25 means for holding the other side of said frame in tight engagement with the other side of said sheathing.

8. In combination, a door construction of the class described, including an exterior sheathing plate formed with an inturned edge constituting a channel, a backing unit constructed to fit against said sheathing plate inside said inturned edge, a member projecting from said backing unit at the free side of the door into the adjacent 30 channel formed by the edge of the sheathing when the sheathing and backing are placed together, the opposite side of the door unit being freely swingable into position against the sheathing plate, supporting hinges for said door, and 40 means passing through said supporting hinges and sheathing plate into the swingable side of said door unit, for the purpose set forth.

9. A door construction of the class described, including an exterior sheathing plate formed 45 with an inturned edge, constituting a channel, a backing unit constructed to fit against said sheathing plate inside said inturned edge, a metal member projecting outwardly from said backing unit at the free side of the door into 50 the channel formed by the adjacent inturned edge of the sheathing plate, the opposite side of the door unit being freely swingable past the adjacent inturned edge of the sheathing plate against the rear face of said sheathing plate, 55 supporting hinges, and means passing through said hinges and into the side of the backing unit opposite the side of the unit carrying the metal member.
